UNITED STATES PATENT OFFICE

155,577

DESIGN FOR A COMBINED COOKING AND DISPLAY CASE

George H. Bushway, North Hampton, N. H.

Application April 22, 1948, Serial No. 145,894

Term of patent 14 years

(Cl. D80—11)

To all whom it may concern:

Be it known that I, George H. Bushway, a citizen of the United States, residing at North Hampton in the county of Rockingham, and State of New Hampshire, have invented a new, original, and ornamental Design for a Combined Cooking and Display Case, of which the following is a specification, reference being had to the accompanying drawing, forming a part thereof, in which:

Fig. 1 is a rear elevation of the cooking and display case showing my new design, and

Fig. 2 is a perspective view showing the front and one side thereof.

The side opposite the side shown in Fig. 2 is substantially similar.

I claim:

The ornamental design for a combined cooking and display case, substantially as shown and described.

GEORGE H. BUSHWAY.
